MOULDING MACHINE FOR THE JOLTING,
SQUEEZING OR SIMULTANEOUS JOLTING
AND SQUEEZING OF MOULDS

Erwin Bührer, Schaffhausen, Switzerland

Application April 16, 1954, Serial No. 423,786

Claims priority, application Switzerland August 8, 1953

5 Claims. (Cl. 22—43)

The present invention relates to a moulding machine in which jolting, squeezing or simultaneous jolting and squeezing are utilized for compacting moulds or for finally compacting precompacted moulds.

The compacting of granular masses has hitherto been achieved by squeezing, by jolting and subsequently squeezing, or by simultaneously applying the two effects.

In the squeezing process, an external squeezing pressure is exerted by means of a press plate on the granular mass which however, owing to friction, is more tightly compacted in the portion adjacent to the press plate than in the more distant portion adjacent to the pattern equipment plate plane. In the jolting process, the speed developed by the granular mass, for instance in free fall is suddenly checked. It is known that due to the inertia of the falling granular mass itself, in contrast to the effects of the squeezing process, said mass attains the highest degree of density in the pattern equipment plate plane.

An additional squeezing effect is obtained by placing a weighting plate on the granular mass during the jolting process. But this additional effect is not in itself sufficient to achieve perfect compaction. A swivelling press fitted on the mould table and acting on the granular mass during the jolting process by means of a press plate designed as a weighting plate failed to give good results in practice because the equipment proved too clumsy and insufficiently accessible.

A number of different suggestions recommend the fitting of hammers or jolting pistons either on the press plate side or on the pattern equipment or mould table side. All these suggestions, which provide for simultaneously squeezing and working the jolting pistons or hammers while the granular mass remains stationary, are erroneously termed jolting presses. In order to distinguish clearly their mode of operation from the simultaneous inertia jolting and squeezing described below, this group of suggestions, in which the granular mass undergoes no modification of its state of movement during the squeezing and working of the hammers or jolting pistons, should be termed squeezing with simultaneous hammering since the blows dealt merely achieve an intermittent increase in the squeezing pressure. In contrast thereto the suggestions in which the granular mass, while subjected to a squeezing pressure, is simultaneously compelled suddenly to modify its state of movement so that the inertia of the granular mass itself is made use of, are termed squeezing with simultaneous inertia jolting or jar-squeezing. Whereas squeezing with simultaneous hammering does not affect inequalities of compaction any more due to friction than squeezing alone, the process of inertia jolting and simultaneous squeezing is able to smooth them out because with inertia jolting the points of maximum compaction are located in an opposite position to those produced by squeezing alone.

In the present invention the press is only linked with the mould table, or with parts attached thereto, during the process of squeezing or simultaneous jolting and squeezing, but otherwise has no material contact with it.

2

The drawings illustrate three embodiments of the object of the invention by way of example, as follows:

Fig. 1 is a side view of a moulding machine drawn partly in section;

Fig. 2 is a top view of Fig. 1;

Fig. 3 shows a second embodiment of part of a moulding machine drawn partly in section;

Fig. 4 is a sectional view taken along the line IV—IV in Fig. 3; and

Fig. 5 shows a third embodiment of part of a moulding machine drawn partly in section.

Referring now to Figs. 1 and 2, there is shown an arrangement in which the jolting equipment R is stationary and the press P can swivel. On the stand or column 1 the swivelling sleeve 2 is supported. The latter has six lugs 3 (Fig. 2) in each pair of which, rods 4 are fixed. On the press P are provided three coupling members in the shape of the arms 6 and 6a, of which the arm 6a has three guide lugs 7 which are supported or guided for upward and downward movement on the rods 4 and rest against the lugs 3 forming seat means when the press is in the position of rest. The press P can swivel round the column 1 by means of the sleeve 2. The mould table 8 of the jolting equipment R carries a pattern equipment 9 on which rests the moulding box 10 filled with a granular mass 11. The mould table 8 rests on buffer bolts 12 which are supported by screws 13 in the foot of the jolting equipment R. The air duct 15 terminates in the cylinder 14a of the foot 14 of the jolting equipment R. The arms 6 and 6a of the press P have claws 64 which engage under the mould table 8 so that when the ram 62 presses against the granular mass the press is coupled to the mould table and the coupling members take up the squeezing pressure. In order to produce the inertia jolting effect the mould table 8 can then move up and down independently of the simultaneously applied squeezing pressure. Consequently three forces act simultaneously in the process of squeezing with simultaneous inertia jolting:

40 (1) Squeezing of the granular mass by the press.

(2) Due to the sudden variation of the state of movement and the inertia of the granular mass, jolting causes a force within the latter.

45 (3) Due to the sudden termination of the state of movement and the inertia of the press ram, jolting causes a force within the latter which acts on the granular mass as an additional squeezing.

Fig. 3 shows equipment for this purpose, combined, by way of example, with a machine having an intermittently rotating table 40, which carries the moulding equipments R, and with a non-pivoting press P associated therewith which is released from its connection when the jolting process is applied and is only coupled to the mould table. The stationary non-pivoting column 55 16 has lugs 17 which carry conical pivot bolts 18. In order to prevent the guiding eyes from impinging violently on the conical pivot bolts 18, a buffer device is provided which can be seen in Fig. 4. In the lugs 51 is disposed a conical bushing 48 which can slide and which rests against the cup springs 49. The conical bushing and the prestressed cup springs 49 are maintained in the lugs 51 by the screws 50. On to the column 16 is connected a guide ring 19 on which rests a spring 20 designed to take up at least part of the weight of the press P. This spring transmits its compression to a ring 21 fixed to the member 22 which is in turn fixed to the sleeve 23 and which is fixed to the member 24. To the member 24 are attached the hook-shaped arms 25 and 25a of which the arm 25 has lugs 51. The lugs 51 in Fig. 3 replace the lugs 7 in Figs. 1 and 2 and the pivot bolts 18 replace the rods 4 employed there. In the threaded bushing 26, which can turn in the member 22, a threaded

bolt 27 holds the cylinder 28 of the press P, which cylinder is at the same time slide-fitted in the member 24 and prevented from rotating. To the threaded bushing 26 is attached a sleeve 29 which has handles 30 and by its rotation enables the press cylinder 28 to be shifted vertically. An air duct 31 leads to the press cylinder 28 wherein a piston 32 with a screw 33 is supported on a piston rod 34 to which is attached a press plate 35. A piston spring 36 rests against a lid 37 of the cylinder 28 and supports the piston in the position of rest. On a slideway 38, centered by the bolt 39, rests a revolving table 40 fitted with several cylinders 41, designed for instance for shockless jolting, in each of which is a counter jolting piston 42, whose mould table 44 is guided by the jolting piston 63 in the counter jolting piston 42 and rests on buffer bolts 43 arranged in the counter jolting piston 42. On the mould table 44 there is a moulding or pattern device 45 with the moulding box 46 filled with a granular mass 47.

The equipment illustrated in Fig. 5 differs from that of Fig. 3 in that the press P can also swivel, as in Fig. 1. The holding device 52 for the press 53 is rotatable and supported on the stand 54 so that it can be turned by means of the cogs 55, 56 and 57. The cog 57 is fixed on the rotary table 58 which carries several jolting devices R.

The moulding machine illustrated in Figs. 1 and 2 operates as follows:

When the press P lies in its swivelled-out position 60 (Fig. 2) the moulding box 10 is set on the jolting press R and the granular mass 11 is poured in. After pre-compressing by the jolting process or even immediately after the moulding box 10 has been filled, the press P is swivelled in to the position shown in Figs. 1 and 2. The press P is subjected to squeezing pressure through the air duct 61 and a valve not shown in the drawing. The squeezing plate 62 presses against the granular mass 11 and thus raises the press P so that the claws 64 of the arm 6, which serve as coupling, come to rest on the underside of the mould table 8. Simultaneously the guide lugs 7 are lifted off the lugs 3 on which they rest in the position of rest (Fig. 1).

By actuating a valve not shown in the drawing compressed air is fed to the air duct 15. The mould table 8 is raised together with the press P and jarred in the known way, while the ram 62 of the press P squeezes simultaneously against the granular mass, the counter-pressure being taken up by the arms 6 and 6a. Upon actuation of suitable valves, after the completion of the compaction process, the pressure media flow out of the ducts 15 and 61. The mould table remains supported on the buffer bolts 12, whereas the squeezing plate 62, which is subject to a spring pressure acting vertically upwards, moves relatively to the press P so that the latter falls until the guide lugs 7 rest on the lugs 3. The claws 64 have simultaneously dropped from the underside of the mould table 8. The press P is now swivelled out in the direction of the arrow 60 (Fig. 2), the finished mould is raised in a known way not shown in the drawing, a new moulding box is set in place and the process is repeated. Depending on the type of mould the granular mass can be compacted by jar squeezing in a single operation without pre-compaction.

The equipment illustrated in Fig. 3 operates in the same way as that of Fig. 1, the only difference being that the press does not swivel because the jolting equipment R revolves round an axis. In the machine illustrated in Fig. 5 both the jolting equipment and the press P swivel round a vertical axis. In the equipment illustrated in Figs. 3 and 5 part of the weight of the press P is taken up by the springs 36 so that the counter jolting piston 43, which is dimensioned for jolting without the press P, can lift the weight to which it is subject. An equipment as illustrated in Figs. 3 and 5 is designed for shockless jolting.

Experiments have shown that the invention operates to greater advantage the higher is the mould to be prepared and/or the pattern equipment to be copied. The principle can be applied to all moulding machines fitted with a jolting equipment.

What I claim is:

1. In a moulding machine for compacting granular material contained in a mould box; a mould table arranged to support said box with said granular material, means arranged below said mould table and operatively connected thereto for jolting said material and thereby pre-compacting the same, squeezing means adapted to assume an upper and a lower location and situated above said mould table, said squeezing means including a cylinder and a ram movable within said cylinder and engageable with said material for final compaction of said material in said box, support means out of contact with said jolting means and said mould table and suspending said squeezing means, said squeezing means being adapted to perform upward and downward movement relative to said support means; said support means including further means to firmly seat said squeezing means in said lower location of the latter, fluid supply means connected to said cylinder for moving said ram into and out of engagement, respectively, with said material in said box, spring-operated coupling means rigidly connected to and depending from said cylinder and terminating in hook-shaped arms, and spring means interposed between said support means and said squeezing means, said hook-shaped arms extending beneath said mould table and being engageable with the latter only upon engagement of said ram with said material in said mould box with said spring means urging said coupling means including said arms to effect rigid interconnection of said squeezing means with said mould table in said upper location, said interconnection being effected solely during final compaction of said material whereby simultaneous jolting and squeezing actions occur, said arms being disengageable from said mould table for completely separating said squeezing means from said mould table, to thereby facilitate seating of said squeezing means on said further means in said lower location and to make available said squeezing means and said mould table for respective independent operations.

2. In a moulding machine for compacting granular material contained in a mould box; a mould table arranged to support said box with said granular material, means arranged below said mould table and operatively connected thereto for jolting said material and thereby pre-compacting the same, squeezing means adapted to assume an upper and a lower location and situated above said mould table, said squeezing means including a cylinder and a ram movable within said cylinder and engageable with said material for final compaction of said material in said box, support means out of contact with said jolting means and said mould table and suspending said squeezing means, said squeezing means being adapted to perform upward and downward movement relative to said support means, said support means including further means to firmly seat said squeezing means in said lower location of the latter, fluid supply means connected to said cylinder for moving said ram into and out of engagement, respectively, with said material in said box, coupling means rigidly connected to and depending from said cylinder and terminating in hook-shaped arms, said hook-shaped arms extending beneath said mould table and being engageable with the latter only upon engagement of said ram with said material in said mould box to effect rigid interconnection of said squeezing means with said mould table in said upper location, said interconnection being effected solely during final compaction of said material whereby simultaneous jolting and squeezing actions occur, said arms being disengageable from said mould table for completely separating said squeezing means from said mould table, to thereby facilitate seating of said squeezing means on said further means in said lower location and

to make available said squeezing means and said mould table for respective independent operations.

3. A moulding machine for compacting granular material contained in a mould box; comprising a mould table arranged to support said box with said granular material, means arranged below said mould table and operatively connected thereto for jolting said material and thereby precompacting the same, squeezing means including a cylinder and a ram movable within said cylinder and operable to finally compact said material in said box, support means out of contact with said jolting means and said mould table and suspending said squeezing means for swivelling movement thereof between a first position relatively remote from said mould table and a second position above said mould table, said support means permitting upward and downward movements of said squeezing means, said support means including further means to firmly seat said squeezing means in a lower location of the squeezing means, fluid supply means connected to said cylinder for moving said ram into and out of engagement, respectively, with said material in said box from above, coupling means rigidly connected to and dependent from said cylinder, said coupling means including hook-shaped arms extending beneath and being engageable with said mould table only upon engagement of said ram with said material when placed in said box to effect rigid interconnection of said squeezing means with said mould table solely during final compaction of said material in which simultaneous jolting and squeezing thereof occur, said coupling means being disengageable from said mould table in order to completely separate said squeezing means from said mould table to seat said squeezing on said further means in said lower location and to thereby permit swivelling movement of said squeezing means into said first position.

4. A moulding machine for compacting granular material contained in a mould box; comprising a mould table arranged to support said box with said granular material, means arranged below said mould table and operatively connected thereto for jolting said material and thereby precompacting the same, squeezing means including a cylinder and a ram movable within said cylinder and operable to finally compact said material in said box, support means out of contact with said jolting means and said mould table and suspending said squeezing means for swivelling movement thereof between a first position relatively remote from said mould table and a second position above said mould table, said support means permitting upward and downward movements of said squeezing means, operable means interposed between said support means and said squeezing means, said support means including further means to

firmly seat said squeezing means in a lower location of the squeezing means, fluid supply means connected to said cylinder for moving said ram into and out of engagement, respectively, with said material in said box from above, coupling means rigidly connected to and dependent from said cylinder, said coupling means including hook-shaped arms extending beneath and being engageable with said mould table only upon engagement of said ram with said material when placed in said box to effect rigid interconnection of said squeezing means with said mould table solely during final compaction of said material in which simultaneous jolting and squeezing thereof occur, said coupling means being disengageable from said mould table in order to completely separate said squeezing means from said mould table to seat said squeezing means on said further means in said lower location and to thereby permit swivelling movement of said squeezing means into said first position, a guide ring extending from said support means to said cylinder, said operable means including a spring seated on said guide ring, said cylinder extending through said guide ring and said spring and having an annular flange forming the upper end of said cylinder, said spring abutting against said annular flange to transmit at least part of the dead weight of said squeeze means to said support means.

5. A machine according to claim 3, further including guide rods mounted on said support means, and slide means connected to said squeezing means and arranged for upward and downward movement along said guide rods together with said squeezing means between said upper and said lower location of the latter.
